UNITED STATES PATENT OFFICE.

IRVING B. SMITH, OF PHILADELPHIA, PENNSYLVANIA, ASSIGNOR TO STOKES & SMITH COMPANY, OF PHILADELPHIA, PENNSYLVANIA, A CORPORATION OF NEW JERSEY.

NOTE-SHEET FOR AUTOMATIC MUSICAL INSTRUMENTS.

No. 875,858.

Specification of Letters Patent.

Patented Jan. 7, 1908.

Application filed June 7, 1905. Serial No. 264,085.

To all whom it may concern:

Be it known that I, IRVING B. SMITH, a citizen of the United States, residing at Philadelphia, in the county of Philadelphia and 5 State of Pennsylvania, have invented new and useful Improvements in Note-Sheets for Automatic Musical Instruments, of which the following is a specification.

My present invention relates to certain 10 new and useful improvements in perforated note sheets for self-playing or automatically operated musical instruments, and has to do more especially with a novel system of marking the sheets to indicate to the performer 15 just which particular expression or tempo controlling device is to be manipulated, and the extent of movement to be given to said device or devices, in order to obtain a certain definite musical effect or expression.

20 In some of the known types of piano players a single lever is employed to control the tempo, or speed of travel of the music sheet; and likewise one or more levers or other devices are employed to control the expression 25 mechanism forming a part of the player, or of the piano itself.

The purpose of the present invention is to provide perforated music sheets with suitable indicating marks or characters representing the above mentioned expression and tempo controlling devices, either or both, and indicating, through their position and relative arrangement one to the other, just 30 which particular device is to be actuated, and 35 the extent and direction of movement to be imparted thereto, in order to obtain a certain definite musical effect or expression.

Briefly and generally stated the invention comprises a perforated note or music sheet, 40 having marks or characters thereon designating an expression controlling device, said marks or characters being located and arranged so that their particular location and position will determine the exact position 45 said device is to assume in order to obtain a certain musical effect.

The invention further comprises a perforated music sheet having marks or characters thereon representing expression controlling devices, said marks or characters indicating through their particular location and position relative to each other and to a line or lines adjacent thereto, just which particular expression device is to be manipulated 50 and the extent and direction of movement to

be imparted thereto, in order to obtain a certain definite musical effect or expression.

In order to enable others to clearly understand, make and use my improvements above indicated, I will now proceed to describe the same in detail, reference being had to the accompanying drawings in which:

Figure 1 represents a face or plan view of a music sheet marked according to the said invention; and Fig. 2 is a similar view showing the use of different indicating marks or characters.

In the drawing the reference numeral 1 designates an ordinary perforated music sheet of common construction and 2, the spool upon which it is wound.

The expression marks or characters now to be described are imprinted or otherwise delineated upon the face of the sheet and may be located at any desired or convenient place thereon, either in the center or along one edge at either side. In the present instance I have shown the marks or characters indicating or representing the expression controlling devices, arranged along the right hand edge of the sheet, and those indicating or representing the tempo controlling device along the left hand edge of the sheet. Obviously, this arrangement may be varied or reversed to suit the convenience of the performer or the particular instrument or instruments with which the sheet is to be used.

I will first describe the marks or characters arranged along the right hand edge of the sheet, which marks or characters represent or indicate the three expression levers for controlling the musical tones in the bass, middle and treble portions of a piano, said levers being the same as those illustrated and described in my patent, No. 777,226, dated Dec. 13, 1904, for expression mechanism for automatically operated musical instruments. Obviously, my improved system of marking perforated music sheets may be employed in connection with a greater or a less number of expression levers without departing from the spirit thereof, the showing here being made only by way of example.

In the drawing the reference numeral 3 designates a part of the expression controlling device for the bass hammers or strings of the piano; 4, the controlling device for the middle range of hammers or strings and 5 the controlling device for the treble strings or hammers. In the system of marking illus-

trated in Fig. 1 of the drawing, each of these controlling devices 3, 4 and 5 is indicated by a legend mark or character which in itself is a conventional representation of the particular expression device on the piano or piano player and is therefore readily recognizable and distinguishable. These legend marks or characters are preferably arranged transversely of the music sheet 1, and adjacent an index, shown, for example, as a line 6, or between the line 6 and a similar indexes line 7, these two lines indicating substantially the extent or range of movement that the expression levers have in actual operation.

15 The line 6 in the particular arrangement shown in the drawing, and for purpose of example only, is designated as an index line, indicative of and taking the place of the substantially normal position of the controlling device of the musical instrument in which the music sheet is incorporated. In some instances it is also desirable to connect the marks or characters 3, 4 and 5 by lines 8, for a purpose presently to appear.

20 25 As before stated, the purpose of the present invention is to provide a system of markings whereby to indicate to the performer just which particular expression device is to be operated and the extent of movement to be imparted thereto in order to obtain a certain definite musical expression or effect, and I will now proceed to describe how these various intelligences may be indicated, it being understood that this illustration is given only by way of example and applies more particularly to those pianos or piano-players wherein separate expression devices are employed to control the bass, the middle and the treble strings or hammers. For clearness in description, I have indicated the markings as "position C", "position D", position "E", position "F", and position "G", but it will be apparent that there may be other positions and that in actual practice the arrangement will be in accord with the musical score.

30 35 40 45 As shown in position C, the three indicating marks or characters 3, 4 and 5, are arranged in the same plane, parallel with and closely adjacent to the upper transverse line 6. This is supposed to be the normal position of the controlling levers and indicates that all the notes will be sounded pianissimo. If now, the musical score shows that notes in the middle range of the piano are to be accented to the full extent, then the music sheet will be marked as indicated in position D, wherein it will be seen that the mark 4 representing the middle range of keys, is shown as depressed; while the marks 3 and 5, representing the bass and treble, are in normal position. If all the notes in the bass, middle and treble are to be played with a forte effect, then all three of the marks 3, 4 and 5 representing the three expression le-

vers, will be shown as depressed to the full extent as indicated in position E. If the musical score indicates that the bass notes are to be sounded fairly soft or pianissimo, the notes in the middle range of the piano moderately loud, and the notes in the treble full loud, then the indicating marks will be represented as in position F, wherein it will be seen that the mark or character 3 is slightly below the line 6, the mark or character 4 about midway between the two lines 6 and 7, and the mark or character 5 closely adjacent the line 7. If the musical score shows that the bass and treble notes are to be played loud, and the middle range of notes soft or pianissimo, then the indicating marks or characters will be arranged as in position G.

45 50 55 60 65 70 75 80 85 90 95 100 105 110 115 120 125 130 I have described above only five indications of changes in the expression devices to obtain different musical effects, but it will be obvious that many other changes may be made which will necessitate corresponding changes in the position of the various expression marks or characters. The amount of depression to be given to the various expression devices will be indicated by the distance between the particular mark or character and its adjacent lines 6 and 7, and the particular device to be operated will be indicated by the position of the marks or characters relative to each other and to the line 6 or 7. The lines 8, which connect the several marks or characters 3, 4 and 5, are to indicate the general relation of the levers or devices at a glance and to assist in making a more or less continuous picture.

Instead of employing marks or characters in the shape of conventional representations of the expression devices, I may employ simple letters such as B, M and T, as indicated in Fig. 2 of the drawing; and these letters may, if desired, be bounded by a circular or other line, as shown. I do not wish to limit myself to any particular character or form of mark, for it will be obvious that this is not material.

On the left hand side of the sheet, as shown in Fig. 1 of the drawing, I have shown a system of marking embodying the principle above set forth, to indicate to the performer just how the tempo lever is to be operated and the extent of movement to be given said lever to cause the music sheet to travel at the desired and proper speed.

In the drawing the reference numerals 12 and 13 designate indexes, shown, for example in the form of lines which extend longitudinally of the sheet 1, and the line 12, for example, may be taken as an index representing and taking the place of the substantially normal position of the tempo lever of the instrument, and between these lines is a legend mark or character 14 designating in a conventional way or otherwise, the tempo

lever of the piano player. The position of this mark relative to either the line 12, or the line 13, will indicate the direction and extent of movement to be imparted to the tempo lever in order to control the speed of the music sheet. For instance, if the indicating mark 14 is closely adjacent the line 13, then it will be apparent that the tempo lever should be moved to cause the sheet to travel fast. If the indicating mark is midway between the lines 12 and 13, this will indicate that the tempo lever should be correspondingly moved, which will cause the sheet to travel at a moderate rate of speed. If the indicating mark is closely adjacent the line 12, this will indicate that the tempo lever is to be moved accordingly so as to cause the sheet to travel slow. Any intermediate position or location of the indicating mark, relative to the lines 12 and 13, will indicate corresponding positions of the tempo lever.

Having thus described my invention, what I claim as new and desire to secure by Letters Patent is:—

1. A perforated note sheet provided at different points throughout its length with indicia each comprising a normal position index and legends co-related thereto and indicative, by reference thereto, of the position with respect to normal which a controlling device of a musical instrument shall sustain to obtain a given musical effect.

2. A perforated music sheet, having thereon at different points throughout its length index lines, and legends arranged adjacent each line and positioned relatively thereto to indicate the exact position a controlling device of a musical instrument is to assume in order to obtain a given musical expression.

3. A perforated music sheet having thereon at different points throughout its length index lines, and legends representing a controlling device of a musical instrument, positioned relatively to each line to indicate the extent of movement to be imparted thereto in order to obtain a certain musical expression.

4. A perforated music sheet having thereon a plurality of separately arranged index lines, and a plurality of sets of legends each representing a separate controlling device of a musical instrument positioned relatively to

each line to indicate the exact position and extent of movement to be imparted to said device in order to obtain given musical effects.

5. A perforated music sheet having thereon at different points along the sheet a plurality of pairs of parallel index lines, and a legend representing a controlling device of a musical instrument, arranged between each pair of lines and indicating by its location relatively thereto, the extent of movement to be given said controlling device in order to obtain a certain definite result.

6. A perforated music sheet, having imprinted thereon at different points throughout its length a plurality of pairs of parallel index lines, and a plurality of sets of legends each legend representing a separate controlling device of a musical instrument one set arranged between each pair of said lines and indicating by their position relatively to each other and to the lines, the extent and direction of movement to be imparted to said devices in order to obtain a given musical effect.

7. A perforated music sheet having imprinted thereon at different points throughout its length a plurality of index lines, and a plurality of sets of legends, each legend representing a separate controlling device of a musical instrument one of said sets positioned relatively to each line to indicate the position and extent of movement to be imparted to said devices in order to obtain given musical effects, and connecting lines between the said legends.

8. A perforated music sheet having thereon indexes arranged at different points throughout its length and a conventional representation of a part of a controlling device located adjacent each index and, indicating by its position on the sheet with relation to said index the extent of movement to be imparted to the said device in order to obtain a given result.

In testimony whereof I have hereunto set my hand in presence of two subscribing witnesses.

IRVING B. SMITH.
